DESIGN FOR AN ABACUS-LIKE TOY

William P. Colvin, New Rochelle, N. Y.

Application April 10, 1947, Serial No. 138,277

Term of patent 14 years

(Cl. D34—15)

To all whom it may concern:

Be it known that I, William P. Colvin, a citizen of United States and a resident of city of New Rochelle, in the county of Westchester and the State of New York, have invented a new, original, and ornamental Design for an Abacus-like Toy, of which the following is the specification, reference being had to the accompanying drawing forming part thereof.

Figure 1 in the drawing is a perspective view of an abacus-like toy showing my new design; and Figure 2 is a vertical section of one of its movable elements taken on line 2—2 of Figure 1.

The reverse side of this toy is a substantial duplicate of that shown in the drawing.

I claim:

The ornamental design for an abacus-like toy, substantially as shown and described.

WILLIAM P. COLVIN.
